INFLATABLE RIDING TOY

William F. Davis, 107 Brown St.,
Tecumseh, Mich. 49286

Filed July 1, 1970, Ser. No. 23,800

Term of patent 14 years

Int. Cl. D21—01

U.S. Cl. D34—15

FIG. 1

FIG. 2

FIG. 2

FIG. 1 is an elevational view of an inflatable riding toy constructed in accord with my design showing the right side, the left side is identical thereto,

FIG. 2 is a front elevational view,

FIG. 3 is a rear elevational view of my new design, and

FIG. 4 is a top view.

I claim:

The ornamental design for an inflatable riding toy, substantially as shown and described.
